UNITED STATES PATENT OFFICE.

JAMES E. SEELEY, OF LOS ANGELES, CALIFORNIA, ASSIGNOR TO SYNCHRONOUS STATIC CO., OF LOS ANGELES, CALIFORNIA, A CORPORATION OF CALIFORNIA.

ELECTRICAL APPARATUS.

No. 802,413.

Specification of Letters Patent.

Patented Oct. 24, 1905.

Application filed July 20, 1904. Serial No. 217,348.

To all whom it may concern:

Be it known that I, JAMES E. SEELEY, a citizen of the United States, residing at Los Angeles, in the county of Los Angeles and State of California, have invented new and useful Improvements in Electrical Apparatus, of which the following is a specification.

This invention relates, primarily, to an apparatus for producing electrical discharges of high frequency and intensity. Such discharges are used for the production of X-ray effects and in various therapeutical and other applications, and my invention is applicable to any of such uses.

15 An important object of the invention is to provide an apparatus for this purpose which will be adapted for operation by either alternating or direct current, so that it can be applied in connection with any of the usual distributing-circuits now in use.

Another object of the invention is to provide for a maximum energy of discharge for a given amount of energy supplied.

25 A further object of the invention is to increase the rapidity of oscillation of the discharge.

Another object of the invention is to provide for adapting the apparatus for operation with alternating supply-circuits of different periodicity.

The accompanying drawing is a somewhat diagrammatic illustration of my invention.

The apparatus comprises an electromagnetic device 1, adapted to receive electric energy 35 from the line-terminals or supply-wires 2 3 and to produce from the direct current or alternating current supplied thereby discontinuous impulses of higher potential, a condenser 4 connected to receive such impulses 40 from the electromagnetic device, an induction device having its primary coil 5 connected to receive the discharge from the condenser and its secondary coil 6 connected to discharge-terminals 7 8 and adapted to produce 45 at such terminals a discharge whose frequency and potential are sufficiently high to give the desired effects, a switch 9 for changing the supply connection of the electromagnetic charging device 1 to adapt the apparatus 50 to direct current or alternating current, a rheostat or equivalent device 10 for regulating the operation of the apparatus or for adapting it to differences in potential of the sup-

ply-circuit, and a switch 11 for making or controlling the connection between the apparatus above specified and the supply-circuit 55 2 3.

The electromagnetic device 1 comprises a core or body 12, which may be made of soft iron wire with suitable windings thereon, and an armature 13, supported in proximity to the end of the core by suitable elastic retracting means, and an interrupter operated by said armature. Said electromagnetic device is preferably wound with two coils 14 15, the 60 wires of which may be side by side.

The switch 9 comprises pivoted conductor-arms 16, 17, and 18 and suitable insulating and operating means therefor. The arms 16 17 are connected by wires 19 20 with opposite ends of the coil 14, and in the position of the switch shown in full lines in the drawing, which is that for operation with an alternating current, these arms contact with terminals 21 22, one of which, 21, is connected to 70 one side of the switch 11, which is assumed to be a double-pole switch, and the other of which, 22, is connected, through rheostat 10, to the other side of said switch 11, thus establishing a supply connection from the line-wires 2 3 to the coil 14, said circuit leading from wire 2 through one side of the switch 11, wire 23 to terminal 21, switch-arm 16, wire 19, coil 14, wire 20, switch-arm 17, terminal 22, wire 24, rheostat 10, wire 26, and 75 the other side of switch 11 to the line-wire 3. Coil or winding 15 is at the same time energized by a parallel connection including the interrupter or circuit-breaker, two of whose terminals 28 29 are connected by a spring 36, 80 also serving as a conductor to the armature 13 aforesaid, the other terminals 30 31 being fixed and being connected, respectively, by a wire 32 to the outgoing side of switch 11 and by wires 33 34 to arm 18 of switch 9, from 85 which the connection is completed by the terminal 39, wire 25, and coil 15 to wire 24 at the other side of the circuit, as hereinafter described. In this position of the switch therefore there is a connection from the line 90 through coil 14 of the electromagnetic device for causing the control or operation of said device and of the interrupter operated thereby in response to the alternations of the alternating current, and there is a parallel connection through the coil 15 and through the 95 100 105

interrupter for producing the interruptions of the inductance-circuit necessary for the setting up of the high-potential impulses which charge the condenser.

- 5 When the switch 9 is moved to the position shown in dotted lines, the arm 16 breaks circuit and the arm 17 makes contact with the terminal 27, connected by wire 25 to one end of the coil 15, whose other end is connected to wire 24 aforesaid, and through the rheostate and wire 26 to the return side of switch 11. Under these circumstances the connection from the line to the electromagnetic device is through the interrupter aforesaid.
- 15 In the position of the switch 9 last referred to arm 18 is in contact with a terminal 35, connected to wire 19. This is the position for operating with direct current, the circuit leading from wire 2 through switch 11 to wire 32, terminals 30 and 28, connection 36 on the armature, terminals 29 31, wires 33 and 34, switch-arm 18, terminal 35, wire 19, coil 14, wire 20, switch-arm 17, terminal 27, wire 25, coil 15, wire 24, rheostat 10, and wire 26 to the other side of the line-switch 11. Thus in this position of the switch 9 the two energizing-coils 14 15 are placed in series and the interrupter is included in the circuit, whereas in the full-line position the two coils are 30 in parallel and the connection to one of them does not include the interrupter. The condenser-circuit comprises the wire 33, leading from the terminal 31 aforesaid to one side of the condenser 4, and a wire 37, leading from 35 the other side of the condenser to the coil 5, whose other end is connected by wire 38 to the terminal 30. The wires 33, 37, and 38, coil 5, and generally the connections of the condenser-circuit should be of large cross-section, so as to present a minimum resistance, and said wires and coil are preferably formed of conducting-tubes to lessen the inductance thereof.

In order to charge the condenser, it is necessary to maintain a connection therewith from the electromagnetic device 1. This connection in the dotted position of the switch 9 is established by the arm 18 making contact with the terminal 35 and in the full-line position of the switch by said arm making contact with the terminal 39, connected to wire 25 aforesaid.

One of the energizing-circuits of the electromagnetic device being independent of the interrupter, when the apparatus is supplied by alternating current the armature will at such times tend to operate responsively or in synchronism with the alternations of such current, and to insure complete synchronism 55 means are provided for regulating the periodicity of vibration of said armature. Such means may consist of an elastic support, such as a ribbon 40, having means for adjusting its tension, being, for example, stretched between a fixed support 41 and a rotatable sup-

port 42, the latter of which is provided with adjusting means, such as an arm 43 and setscrew 44, for adjusting its angular position, and thereby varying the tension of the ribbon 40, so that the free vibration of the armature under the influence of its weight and of said tension will correspond with the frequency of the alternating current being used. It is desirable that the apparatus should be so placed that the ribbon 40 stands "on edge" 75 to allow the heat from the contacts to be carried off by the ascending air-currents.

The terminals 30 31 of the interrupter may be formed as screws to permit adjustment thereof. The object of providing the two sets 80 of terminals 28 30 and 29 31 is to give the effect of a long break with relatively small travel of the interrupter.

In using the apparatus with direct current the switch 9 is placed in dotted-line position, and the charging-current passes through the said switch, through the interrupter, the electromagnetic device 1, and the rheostat in the manner above set forth, thereby causing the interrupter to be vibrated and repeatedly interrupting the charging-current. At each interruption there is a sharp rise of potential between the two sides of the circuit, owing to the kick or self-inductive impulse of the electromagnetic device. This impulse is transmitted to the condenser, passing, for example, from line 2, switch 11, wires 32 38, coil 5, wire 37 to condenser 4, the connection leading from the other side of the condenser through wires 33 34, arm 18, wire 19, coil 14, wire 20, arm 17, wire 25, coil 15, wire 24, rheostat 10, wire 26, and switch 11 to line 3, the two coils 14 15 thus being in series and exerting their combined effect in charging the condenser. As soon as this self-induction impulse has reached its maximum 105 and has correspondingly charged the condenser the potential in the electromagnetic device will begin to fall and the condenser will begin to discharge through the condenser circuit and coil 5. At this moment or immediately thereafter the interrupter will close a condenser discharge-circuit at the terminals 28, 30, 29, and 31, the discharge passing from the condenser through wire 33, contacts 31 29, conductor 36, contacts 28 30, wire 38, coil 5, and wire 37 to the other side of the condenser. This discharge-circuit will be of extremely low resistance, as it does not include any part of the charging-coils 14 15.

The primary inducing-coil 5 is preferably 120 formed with very few turns, thus decreasing the resistance to the minimum. Owing to the low resistance of this circuit, the oscillatory discharge therein will have a correspondingly high periodicity, and high frequencies—say 125 several hundred thousands per second—can be obtained. It is essential to this effect that the interrupter should close contact as near as possible at the time of discharge, so that the condenser will discharge upon a closing 130

and not upon an opening contact, and the discharge-circuit is thus of a minimum resistance.

When the apparatus is to be used with alternating supply-circuits, the switch 9 is moved to the full-line position, so that the coil 14 will be energized from the line independently of the interrupter, so that the magnetic oscillations in the core 12 will be in correspondence with the alternating current. The coil 15 will also be energized from the line in parallel with coil 14 and through the interrupter, and the elastic armature-support 40 should be adjusted, as above described, so that the armature will freely vibrate in synchronism with the alternating current and the coils 14 and 15 will operate in synchronism, the coil 14 serving to control the rate of vibration. The oscillations in magnetic flux in the core 12 result in corresponding electrical oscillations in the condenser-circuit, which is connected to the ends of the coils 14 and 15, these impulses passing from line 2 through wires 32 38, coil 5, wire 37 to one side of the condenser and from the other side thereof through wire 34, arm 18, wire 25, coil 15, wire 24, rheostat 10, and wire 26 to line 3. At the moment when the condenser has received a charge through this connection the armature 13 allows the interrupter to close the circuit, thus establishing a discharge-circuit for the condenser independent of the electromagnetic device 1, said discharge-circuit leading from the condenser through wire 33, terminals 31 29, spring 36, terminals 28 30, wire 38, coil 5, and wire 37 to the other side of the condenser. The change in connections made by the switch 9 in changing from direct to alternating current serves, first, to cut out the interrupter 40 from the supply connection for one energizing-coil, so as to enable the alternating current to control the rate of vibration of the armature, and, in the second place, to reduce the number of turns of windings in series in the energizing-circuit by placing the two coils in parallel relation. This is necessary for the reason that in an alternating circuit the mean, or effective electromotive force is of course much less than the maximum electromotive force, so that in changing from direct to alternating current of the same nominal potential the turns of winding must be decreased correspondingly to give the same magnetizing effect. In the form of winding shown this reduction is in the ratio of two to one, which I have found to work well in practice, as it gives substantially the same discharge effect with alternating and direct currents of approximately the same nominal potential. In order that the closure of the contacts in the condenser discharge-circuit may be rightly timed as far as possible, an iron or conducting shell 45 may be provided around the magnetic device 1 to vary or control the electromagnetic lag therein and by consequent ef-

fect on the armature 13 bring the time of closure as near as possible to the time of beginning of the discharge.

What I claim is—

1. In an electrical apparatus for the purpose described, an electromagnetic device for generating impulses by self-inductive action, and a plurality of energizing connections for said device adapting the same for supply-currents of different effective electromotive force. 70

2. In an electrical apparatus for the purpose described, an electromagnetic device for generating impulses by self-inductive action, a plurality of energizing connections therefor, including, respectively, a different number of turns of winding, and a switch for bringing one or the other of such connections into operation. 80

3. An electrical apparatus for the purpose described, comprising an electromagnetic device for generating impulses by self-inductive action, an interrupter operated by said electromagnetic device, a circuit in energizing connection for said electromagnetic device, including said interrupter and an energizing connection for said electromagnetic device independent of said interrupter, and a switch for bringing one or the other of such energizing connections into operation. 85

4. An electrical apparatus for the purpose described, comprising an electromagnetic device for generating impulses by self-inductive action, energizing connections for said electromagnetic device, respectively including different numbers of turns of winding of said 100 device, and an interrupter operated by said electromagnetic device and included in the energizing-circuit having the lesser number of turns. 95

5. An electrical apparatus for the purpose described, comprising an electromagnetic device for generating impulses by self-inductive action, energizing connections for said electromagnetic device, respectively including different numbers of turns of winding of said 110 device, a condenser-circuit connected to include the windings of both of said energizing connections in series, and a discharge-circuit inductively connected to said condenser-circuit. 105

6. An electrical apparatus comprising a condenser, charging connections therefor including an electromagnetic induction device, and a vibratory interrupter operated by said device, and an energizing connection for the 120 induction device independent of the interrupter for control thereof by alternating current. 115

7. An electrical apparatus comprising a condenser, charging connections therefor including an electromagnetic induction device, a vibratory interrupter operated by said device, an energizing connection for the induction device independent of the interrupter for control thereof by alternating current, 125 130

and means for adjusting the rate of vibration of said interrupter.

8. An electrical apparatus comprising a condenser, charging connections therefor including an electromagnetic induction device, a vibratory interrupter operated by said device, an energizing connection for the induction device independent of the interrupter for control thereof by alternating current, means for adjusting the rate of vibration of said interrupter consisting of an elastic tensile support therefor, and means for adjusting the tension of said support.

9. An electrical apparatus comprising a condenser, charging connections therefor including an electromagnetic induction device, a vibratory interrupter operated by said de-

vice, an energizing connection for the induction device independent of the interrupter for control thereof by alternating current, means for adjusting the rate of vibration of said interrupter consisting of an elastic ribbon supporting the armature thereof, a rotatable support for one end of the ribbon, and set-screw means for adjusting the rotary position of said support.

In testimony whereof I have hereunto set my hand, at Los Angeles, California, this 13th day of July, 1904.

JAMES E. SEELEY.
